EGG CARTON

Richard F. Reifers, New Canaan, Conn., and Henry A. Lord, Palmer, Mass., assignors to Diamond National Corporation, New York, N.Y., a corporation of Delaware

Filed Sept. 4, 1962, Ser. No. 71,556

Term of patent 14 years

(Cl. D58—13)

FIG. 1.

FIG. 2.

FIG. 5.

FIG. 4.

FIG. 3.

FIG. 1 is a perspective view of the outside of an open egg carton showing our new design;

FIG. 2 is a perspective view of the inside of said carton;

FIG. 3 is an open end elevational view of said carton;

FIG. 4 is a closed bottom perspective view thereof; and

FIG. 5 is a closed end elevational view thereof.

The characteristic feature of our design resides in the distinctive appearance in the cells which include on the central post inner wall a large intermediate oval area within which is a smaller and narrower oval in combination with outer side walls of the cells which include on their inner faces elongated convex areas rising from the

cell floors to just short of the upper cell edge and in which the upper portion of the convex areas have superimposed oval areas somewhat similar to the post wall areas.

We claim:

The ornamental design for an egg carton, as shown and described.
